US0D1054436S

(12) **United States Design Patent** (10) **Patent No.:** **US D1,054,436 S**
Chou et al. (45) **Date of Patent:** **** Dec. 17, 2024**

(54) **DISPLAY SCREEN OR PORTION THEREOF WITH GRAPHICAL USER INTERFACE**

(71) Applicants: **SHANGHAI MAGIMA DIGITAL INFORMATION CO., LTD.**, Shanghai (CN); **BIBO NETWORK, LLC.**, San Jose, CA (US)

(72) Inventors: **Jen-Chung Chou**, Shanghai (CN); **Qingyun Chen**, Shanghai (CN)

(**) Term: **15 Years**

(21) Appl. No.: **29/844,376**

(22) Filed: **Jun. 28, 2022**

(30) **Foreign Application Priority Data**

Dec. 30, 2021 (TW) 110307204

(51) LOC (14) Cl. **14-04**

(57) **CLAIM**

The ornamental design for a display screen or portion thereof with graphical user interface as shown and described.

DESCRIPTION

FIG. 1 is a front view of a first embodiment of a display screen or portion thereof with graphical user interface showing our new design;

FIG. 2 is a front view of a second embodiment of a display screen or portion thereof with graphical user interface showing our new design;

FIG. 3 is a front view of a third embodiment of a display screen or portion thereof with graphical user interface showing our new design; and,

FIG. 4 is a front view of a fourth embodiment of a display screen or portion thereof with graphical user interface showing our new design.

The outermost broken lines in the figures show a display screen or portion thereof, and form no part of the claimed design. The other broken lines in the figures show portions of the graphical user interface that form no part of the claimed design.

1 Claim, 4 Drawing Sheets
